(57) **CLAIM**

The ornamental design for a handheld spray nozzle, as shown and described.

DESCRIPTION

FIG. 1 is a top isometric view of a handheld spray nozzle. FIG. 2 is a bottom isometric view thereof. FIG. 3 is a right side elevation view thereof. FIG. 4 is a left side elevation view thereof. FIG. 5 is a top plan view thereof. FIG. 6 is a bottom plan view thereof. FIG. 7 is a front elevation view thereof; and, FIG. 8 is a rear elevation view thereof. The dash-dash broken lines illustrate portions of the handheld spray nozzle that form no part of the claimed design. The dash-dot-dash broken lines, which define the bounds of the claimed design, form no part of the claimed design.
